UNITED STATES PATENT OFFICE.

HENRY CLAY WRISTEN AND JAMES WILLIAM HENDERSON, OF DEXTER, NEW MEXICO.

LATCH FOR DOUBLE-ACTING PUMPS.

1,218,152.

Specification of Letters Patent.

Patented Mar. 6, 1917.

Application filed October 15, 1915. Serial No. 56,123.

To all whom it may concern:

Be it known that we, HENRY C. WRISTEN and JAMES W. HENDERSON, citizens of the United States, residing at Dexter, in the 5 county of Chaves, State of New Mexico, have invented a new and useful Latch for Double-Acting Pumps, of which the following is a specification.

The device forming the subject matter of 10 this application is a means for lowering and holding a pump within a well casing, the device being of peculiar utility in connection with a pump of that sort shown in our co-pending application Serial No. 12,368, 15 filed March 5, 1915.

The invention aims to provide a novel latch structure which, being actuated by a movable element of the pump, will serve to hold the pump in place in the well casing.

20 The invention aims to improve the latch mechanism whereby the pump is held in place.

With the above and other objects in view which will appear as the description proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings:—

Figure 1 shows in longitudinal section, a 35 double acting pump wherewith the latch mechanism forming the subject matter of this application has been assembled;

Fig. 2 is a side elevation of the latch mechanism and parts whereby the latch 40 mechanism is carried and actuated;

Fig. 3 is a section on the line 3—3 of Fig. 2;

Fig. 4 is a section on the line 4—4 of Fig. 2;

45 Fig. 5 is an elevation of the latch mechanism, the structure being viewed at right angles to the showing of Fig. 2;

Fig. 6 is a plan showing the cross arm which constitutes a part of the means for 50 locating and holding in place the foot valve.

In order that the nature and the operation of the present invention may be clearly understood, there are shown in the drawings, sundry elements constituting a part of 55 the double acting pump disclosed in our prior application Serial No. 12,368 above

alluded to. Those parts of the structure described in and covered by our earlier application will be mentioned briefly, proper indication being made at the point where 60 those elements giving novelty to the present application appear.

In the accompanying drawing, the numeral 1 indicates a well casing constituting a pump barrel. Mounted to reciprocate to- 65 ward and away from each other in the casing 1 are pistons 3 and 4 provided with upwardly opening valves 8. Attached at its lower end to the piston 4 is a double rack bar 9 having opposed teeth 10, the rack bar 70 9 passing through a yoke 16 held in place in the well casing 1 by the latch mechanism forming the subject matter of this application. A pair of opposed rods 17 are slidably mounted in the piston 4, the lower ends of 75 the rods being secured to the piston 3. The inner or adjacent edges of the rods 17 are equipped with racks 22. The racks 22 and the teeth 10 of the double rack bar 9 mesh into gear wheels 24, rotatably connected 80 with the yoke 16 by means of axles 25, the gear wheels 24 being located within the contour of the yoke 16.

The foregoing details appear in our prior application above alluded to, and no novelty 85 is claimed for them in this application, saving in so far as they may coact with elements to be described hereinafter.

In practical operation, when the rack bar 9 is reciprocated, reciprocating motion will 90 be transmitted to the rods 17, the pistons 3 and 4 being caused to approach and move away from each other.

In carrying out the present invention, the sides of the yoke 16 are equipped with ears 95 2. Pivot elements 5 are mounted in the ears 2 and in the side portions of the yoke, latches 6 being mounted to swing on the pivot elements, the latches being supplied adjacent their lower ends and upon their 100 outer edges with teeth 7 adapted to engage the well casing 1. Four latches 6 are employed, and the latches at the opposite sides of the yoke 16 are connected with each other by means of links 11, the outer ends of 105 which are united with the latches by means of pivot elements 12, the inner ends of the links 11 being united by means of pivot elements 14.

The double rack bar 9 carries an upper 110 lug 15 and a lower lug 19. These lugs if desired may be detachably united in the

rack bar 9 and may be held therein by set screws 20 or in any other suitable manner. The yoke 16 preferably is bulged outwardly at the sides, as indicated at 50, so as to permit the lower lugs 19 to pass upwardly through the yoke and engage the lower edges of the links 11, for a purpose to be set forth hereinafter.

In practical operation, the pump is lowered into the well casing 1 to the desired point, and then a forcible downward movement is given to the rack bar 9, whereupon the lugs 15 thereof will engage with the links 11, forcing the same into alinement, and swinging the latches 6 outwardly, until the teeth 7 bite into or engage the well casing 1.

When the rack bar 9 is moved upwardly, the lugs 19 will engage the lower edges of the links 11, thereby swinging the links upwardly and swinging the lower ends of the latches 6 inwardly, so that the teeth 7 of the latches are freed from the well casing.

It is to be understood, of course, that during an ordinary stroke of the rack bar 9, the lugs 19 and 15 do not coat with the links 11, such an operation taking place only when the bar 9 is given an unduly long stroke either upwardly or downwardly.

Previous to the mounting of the pump in the well in the manner hereinbefore described, the foot valve is seated in the bottom of the well casing 1. This portion of the structure embodies a platform 21 on which is operatively mounted a foot valve 26. Secured to the platform 21 is an arched, upwardly extended frame 27 having downwardly converging arms 28, the frame 27 carrying a stem 29 threaded or otherwise adapted to coat with a tube or rod (not shown) whereby the valve structure may be lowered to the desired point within the well casing. A cross arm 30 is provided, the same having notches 31 in its ends, the notches 31 receiving the downwardly, converging arms 28 of the frame 27. In the extremities of the cross arm 30, elongated slots 32 are formed, the same receiving guide pins 33 mounted in the sides of jaws 34 having teeth 35 adapted to engage the well casing 1. An abrupt downward movement of the frame 27 will cause the arms 28 to coat with the jaws 34, pushing the same outwardly, and causing the platform 21 to be lodged firmly within the casing 1.

Having thus described the invention, what is claimed is:—

1. In a device of the class described, a tubing; a yoke adapted to be lowered into

the tubing; a latch carried by the yoke and 60 coacting with the tubing to hold the yoke in the tubing; a piston structure slidable in the yoke and coacting with the tubing; and interengaging elements on the piston structure and the latch to move the latch into 65 casing engaging position when the piston structure is moved a distance in excess of its normal movement.

2. In a device of the class described, a 70 tubing; a yoke adapted to be lowered into the tubing; a latch carried by the yoke and coacting with the tubing to hold the yoke in the tubing; a piston structure slidable in the yoke and coacting with the tubing; and interengaging elements on the piston structure and the latch to move the latch out of 75 casing engaging position when the piston structure is moved a distance in excess of its normal movement.

3. In a device of the class described, a 80 tubing; a yoke adapted to be lowered into the tubing; a latch carried by the yoke and coacting with the tubing to hold the yoke in the tubing; a piston structure slidable in the yoke and coacting with the tubing; and 85 interengaging elements on the piston structure and on the latch coacting to move the latch into and out of casing engaging position when the piston structure is moved in opposite directions beyond its normal scope. 90

4. In a device of the class described, a tubing; a yoke adapted to be lowered into the tubing; a pair of latches pivotally carried by the yoke and coacting with the tubing to hold the yoke in the tubing; a flexible 95 connection uniting the latches; a piston structure slidable in the yoke and coacting with the tubing; and projections on the piston structure, the projections being adapted to engage, respectively, with the upper and 100 lower edges of the flexible connection.

5. In a device of the class described, a tubing; a yoke adapted to be lowered into the tubing; latches pivotally carried by the yoke and coacting with the tubing to hold 105 the yoke in the tubing; a flexible connection uniting the latches; and a reciprocating element having spaced projections adapted to engage the upper and lower edges of the connection, respectively, at different times. 110

In testimony that we claim the foregoing as our own, we have hereto affixed our signatures in the presence of two witnesses.

HENRY CLAY WRISTEN.
JAMES WILLIAM HENDERSON.
